UNITED STATES PATENT OFFICE.

HENRY A. WISE WOOD, OF NEW YORK, N. Y., ASSIGNOR TO WOOD NEWSPAPER MACHINERY CORPORATION, OF NEW YORK, N. Y., A CORPORATION OF VIRGINIA.

MACHINE FOR FINISHING TUBULAR PRINTING PLATES.

Application filed June 22, 1921, Serial No. 479,636. Renewed January 4, 1926.

This invention relates to a machine for finishing the so-called tubular printing plate which is a plate consisting of a nearly complete tube or cylinder with a longitudinal slit, usually from end to end. This machine is particularly adapted for finishing the plates produced in accordance with my application for patent on a machine and plant for casting and cooling tubular stereotype printing plates, Serial No. 462,733, filed April 19, 1921, but it is capable of use for finishing of other plates of a general similar form.

The principal objects of the invention are to provide a machine for finishing plates of this general character; to provide means whereby the whole operation of finishing can be controlled by two hand levers and all the operations will be stopped automatically at the proper time, certain mechanisms being automatically unlocked for that purpose; to provide improved automatic connections for this purpose and generally to provide a machine of this character which will comprise relatively few parts.

Reference is to be had to the accompanying drawings in which

Fig. 1 is a longitudinal horizontal central sectional view of a finishing machine constructed in accordance with this invention;

Fig. 2 is a longitudinal vertical sectional elevation through the center of the drive shaft showing the connections for operating it;

Fig. 3 is a perspective view showing the manner of placing the printing plate in position and locating it;

Fig. 4 is a transverse sectional view on the line 4—4 of Fig. 1;

Fig. 5 is a transverse sectional view on the line 5—5 of Fig. 1;

Fig. 6 is an outside elevation of the saw drive operating levers and connections;

Fig. 7 is a plan of the same;

Fig. 8 is an elevation similar to Fig. 6 showing the clutch operation for the saw drive and the shaver drive;

Fig. 9 is a section on line 9—9 of Fig. 8, and

Fig. 10 is a section on the line 10—10 of Fig. 8.

I have shown the invention as comprising a frame preferably in the form of an enclosed casing 10 in which practically all the mechanism is located. At one end of

this frame is a tubular socket or plate support 11 constituting a part of the frame. In the bottom this is provided with longitudinal ways in which is located a slide 12 having a stop 13 on one end in the form of a pair of projections. This slide has a bracket 14 connected by a link 15 with a lever 16 which is adapted to be operated by hand to move the slide back and forth. When the slide is moved back to the position shown in Fig. 2, the printing plate P, with its slit located along the bottom edge, is moved in by hand or otherwise over the slide 12, which at that time is stationary and constitutes a guide for it. The plate is moved in until its rear end engages the stop 13 which properly positions the plate in the machine.

The mechanism for operating on the plate is located inside the plate at this point and the driving mechanism in the casing beyond it. After the tail is cut off and the plate shaved and trimmed in this position, the handle 16 is manipulated to move the slide 12 outwardly to the left in Figs. 1, 2 and 3 and the plate thus ejected far enough so that it will be left on the shaving bar 18 from which it can be removed by hand over the bracket 19.

The machine is provided with a power shaft 20 which receives power from any desired source through a sprocket chain 21 or the like. This shaft is provided with two clutches 22 and 23. The clutch 23 is adapted to connect the shaft 20 with a bevel gear 24 otherwise loose thereon. This gear meshes with a bevel gear 25 on a shaft 26 located transversely across the rear end of the machine. On this shaft there is a worm 27 which drives a worm gear 28. This worm gear is located on the main shaft 30 of the machine. This shaft is located in bearings, one at the rear end of the casing, and the other mounted on the projecting bracket 19 at the front end.

This shaft is provided with a shaving bar 18, above specified, which has two transverse ends 31 integrally connected with it and the shaft. The shaving bar receives the plate on it when the plate is inserted, then rotates a complete revolution, and leaves the plate in position to be removed as stated above. Further features of the shafts themselves will be described below, but it is sufficient to indicate that the shaving bar 18 is provided with the shaving blade 32 which

has an edge trimming projection 33 thereon. This shaving bar 18 rotates with its cutters 32 and 33 and the plate is held stationary in the support 11 by the guide 12.

Referring now back to the worm gear 28 by which the shaft 30 is driven slowly, it is to be seen that this is recessed on one side and provided with a cam track 34, which is circular but has an outwardly extending offset or pocket 35. Running on this cam is a roller 36 on a lever 37 pivoted on and projecting through the stationary frame 10. Connected with the outer end of this lever is a link 38 which, in turn, is pivoted to a bell crank 39. On the latter is a pin operating the clutch 23. A spring 40 normally holds the outer end of the bell crank down and the clutch disconnected but this can only be done when the roller 36 is in the offset 35. The bell crank 39 has an operating handle 41 by which it can be worked.

The operation of the machine is controlled through a handle 42 mounted on a slide 43. This handle is capable of moving from its normal position shown in dotted lines at 42 in Fig. 7 to two other positions designated 42^a and 42^b in that figure. This slide 43 has an offset 44 which engages a surface 45 on a lever 46, as the operating lever 43 moves from the position 42 to the full line position 42^a in Fig. 7, and swings that lever to the left. This lever is connected with the clutch 22 and therefore this action swings the clutch in. A spring 47 normally holds the clutch out and the surface 45 in contact with either the high or low surface of the offset 44 according to the position of the operating handle 42.

When the clutch 22 is thrown in it connects with the shaft 20 a gear 48 which passes through the frame 10 and drives a spur gear 49 inside. This gear 49 is mounted to rotate on the shaft 30 and is provided with a sleeve or casing 50 which contains mechanism inside. It is provided with an internal gear 51 meshing with a pinion 52 on a shaft 53. It will be obvious from an inspection of this gearing that it rotates at a much higher speed than the main shaft 30. This shaft 53 has bearings in the ends 51 which are fixed with respect to the shaft 30. Thus the rotation of the gear 51 rotates the gear 52 on its own axis at a higher speed even if the shaft 30 is rotating. The shaft 53 is provided with two brackets 54 having bearings, the whole being capable of turning on the shaft 53 as a center. In the bearings there is a shaft 57 on which the cutting off saw 59 is mounted. On this shaft also is a gear 58 which constantly meshes with the gear 52 in all positions and therefore the saw 59 is rotated constantly when the clutch 22 is thrown in.

Integrally connected with, or otherwise fitted into, one of the brackets 54 is an arm

65. This is provided with a bend which swings on the inside circular surface of a cam 61 which is of general circular form and is located to oscillate in the frame 10 in a manner that will be described. This cam 70 has a notch 63 and the arm 65 has a tooth 64, the purpose of which is to provide for swinging the saw into an outer cutting position. A roller 66 on the arm 65 rotates on the inside surface of a stationary cam 68 located adjacent to the oscillating cam 61. This stationary cam has a depression 67 in which this roll will rest to withdraw the saw from cutting position. A spring 70 keeps the roll in this depression unless otherwise forced out of it. It will be seen therefore, that by the manipulation of the cam 61, that is, turning it from its normal position, this roll will be forced outwardly and the cutting saw moved while it is rotating into the position shown in Figs. 2 and 5 to cut through the plate P.

I will now describe the mechanism for operating the parts just described. On the side of the gear 28 there is a cam projection 71. As the gear rotates through a complete revolution and comes to the point of completing it, this projection engages a lever 72 having a beveled end and moves it from the position shown in Fig. 6 to the left at the bottom and consequently to the right at the top. This lever is pivoted on a stud 72^a carried on the casing 10 and projects through it into a position to normally engage the straight edge of the gear 28. When the top of the lever moves to the right automatically in the manner specified, it carries with it a rod 73 which is otherwise pressed by a spring 74 into the position shown in Fig. 6. This draws this rod to the right in both Figs. 6 and 7 and the result is that it swings an arm 75 with it as it is pivoted to that arm. This withdraws a stop tooth 79 from the notch 80 in the operating slide 43 and allows a spring 76 to move this slide back to the position 42 indicated in Fig. 7.

It will be noted that this slide 43 has a slot 81 and through this slot projects a pin 82 which pin is mounted on the oscillating cam 61 and moves it with a lost motion as indicated by the length of the slot 81. A spring 83 mounted on a rod 84 normally forces this pin over as indicated in Fig. 7. The end of this rod 84 has a bearing at the top of the pin 82. I have shown a guide 85 on the slide 43.

The operation of the device is as follows:

After the plate P is cooled it is pushed from the cooling stand, or otherwise placed, in the finishing machine by locating it on the projecting end of the shaving bar 18 and shoving it into the plate rest 11 with its slot at the bottom guided by the guide 12. It moves up against the stop 13 and is thereby

positioned in place. All the shafts at this time are stopped with the exception of the shaft 20. The operator now pushes the handle 42 in from the position 42 to the position 42^a. The first effect of this is to move the lever 46 and force in the clutch 22. This starts the gear 48 to rotating and, by the mechanism above described, rotates the saw 59 but the saw at this time is not in cutting position. The next operation is to push the handle 42 further in to the position indicated at 42^b. This causes the end of the slot 81 to engage the pin 82 and swing the cam 61 a short distance around. Then the notch 63 in this cam ring forces the surface 64 on the arm 65 forward and advances the arm 65 from the dotted to the full line position in Fig. 5. This swings the structure around so as to bring the rotating saw 59 into contact 20 with the interior surface of the plate and causes it to commence to cut through the plate. This also lifts the roll 66 out of the depression 67 in the stationary cam 68 so that the whole structure can run on the axis of the 25 main shaft 30 which before was prevented by the position of the roll 66 in that depression.

When the handle 42 reached the position 42^a as above indicated the latch 79 was forced into the notch 80 by the spring 81 automatically. After the saw 59 has reached its cutting position the handle 42 is held in the position 42^b until the operator has pulled up on the handle 41 throwing the clutch 23 into operation. This motion of raising the handle 41 and thus raising the long arm of a bell crank 39 throws the roll 36 out of the notch 35 in the cam 34 so as to permit of this cam rotating. In other words, the cam is unlocked and the clutch operating the shaft 30 started by the same means, that is, the lifting of the handle 41. Therefore, the shaft 30 carrying the shaver bar 18 starts to rotate and the shaving knife 32 and trimming tooth 33 rotate together, while the 45 saw also rotates around with the usual planetary motion. Thus, the tail is sawed off and the plate shaved and beveled.

When the shaver bar 18 starts to rotate the spring 83 forces the pin 82 from the position 50 it has occupied back to the full line position in Fig. 7 and the spring 76 forces the slide 43 back to its full line position. When the shaver bar 18 has completed one revolution, thus completely finishing the plate, the 55 spring 40 automatically snaps the roll 36 into the notch 35 in the cam 34 and disengages the clutch 23, thus stopping the planetary rotation and the entire rotation of the main shaft 30. At the same time the projection 71 engages the lever 72, pulls the rod 73 back, thus overcoming the action of the spring 74 and withdrawing the tooth 79 from the notch 80. The spring 76 then immediately acts to force the slide 43 to the extreme 60 lower position in Fig. 7, which is the posi-

tion of the handle indicated in dotted lines at 42. This is the original and normal position when the machine is not in action. This permits the spring 47 to withdraw the clutch 22 and stop the gear 48. This stops 70 the rotation of the saw spindle. At the same time the roller 66 is forced into the depression 67 in the cam 61 by the spring 70 and retracts the saw so that it is no longer in contact with the plate. 75

The handle 16 is then moved down, drawing forward the slide 12. The projections 13 on the slide which engage the rear of the plate act to withdraw the plate out over the cutter bar 18 from which it is easily removed 80 as the bracket 19 has a thin cross-section below its bearing to permit of the plate being drawn entirely out of the machine axially.

In this way, the operations are entirely 85 automatic with the exception of the operation of two levers 42 and 41. The device is fool proof, for if these levers are operated in the wrong order no harm can result on account of the locking devices connected with the gears that have been described. 90

Although I have described and illustrated only a single form of the invention I am aware of the fact that modifications can be made therein by any person skilled in the art without departing from the scope of the invention as expressed in the claims. Therefore, I do not wish to be limited to all the details herein shown and described but what I do claim is:—

1. In a machine for finishing tubular stereotype printing plates, the combination 100 with a stationary cylindrical support for a plate, of a guide longitudinally located therein having means for engaging the opposite edges of the longitudinal space in the plate and guiding it into proper position.

2. In a machine for finishing stereotype printing plates, the combination with a support for a plate, of a guide longitudinally located therein centrally at the bottom of the 105 support for engaging the plate, said guide having a limit stop thereon engaging the end of the plate.

3. In a machine for finishing stereotype printing plates, the combination with a support 115 for a plate, of a guide longitudinally located therein for engaging the plate, said guide having a limit stop thereon engaging the end of the plate, and means for moving said guide to eject the plate.

4. In a machine for finishing tubular stereotype printing plates, the combination with a stationary cylindrical support for a plate, of a guide longitudinally located therein for engaging the plate, said guide being 125 longitudinally reciprocable with the plate.

5. In a machine for finishing tubular stereotype printing plates, the combination with a stationary cylindrical support for a plate, of a guide longitudinally located 130

therein for engaging the plate, a shaving knife shaft passing through said support and rotatable therein, and a shaving bar located on the shaft in position to move around edge-wise in the support for carrying a shaving knife.

6. In a machine for finishing stereotype printing plates, the combination with a support for a plate, of a longitudinal shaft for carrying finishing devices, a cam on the shaft having an offset pocket, and a movable stop adapted to engage in the pocket to lock the shaft in stationary position.

7. In a machine for finishing stereotype printing plates, the combination with a support for a plate, of a longitudinal shaft for carrying finishing devices, a circular track fixed on and concentric with the shaft having a pocket, a lever having a roll thereon adapted to run on said track and enter the pocket to lock the shaft, and a starting lever connected with the first named lever for withdrawing the roll from the pocket to unlock the shaft.

8. In a machine for finishing stereotype printing plates, the combination with a support for a plate, of a longitudinal shaft for carrying finishing devices, a cam on the shaft having an offset pocket, a movable stop adapted to engage in the pocket to lock the shaft in stationary position, a starting lever connected with the stop for withdrawing it to unlock the shaft, a clutch for connecting the shaft with a source of power, and means connected with the starting lever for throwing in the clutch when the stop is withdrawn.

9. In a machine for finishing stereotype printing plates, the combination with a support for a plate, of a longitudinal shaft for carrying finishing devices, a clutch for connecting the shaft with a source of power, means for locking the shaft, a starting lever, and means operated by the starting lever for unlocking the shaft and throwing in the clutch.

10. In a stereotype plate finishing machine, the combination with the shaving knife shaft, of a clutch for connecting it with a source of power, a cam track rotatable with the shaft having a pocket, and means whereby when the shaft has made a complete rotation the clutch will be thrown out automatically and introduced into the pocket for locking the shaft against rotation.

11. In a stereotype plate finishing machine, the combination with the shaving knife shaft, of a clutch for connecting it with a source of power, a cam track rotatable with the shaft, and means whereby when the shaft has made a complete rotation the clutch will be thrown out automatically and the shaft locked.

12. In a machine for finishing stereotype printing plates, the combination with a support for a plate, of a longitudinal shaft for

carrying finishing devices, a wheel on said shaft for rotating it, a planetary saw shaft supported by the first named shaft, a clutch for connecting the saw shaft with a source of power, and means on said wheel for throwing out said clutch automatically when the first shaft has completed a revolution.

13. In a stereotype plate finishing machine, the combination with the shaving knife shaft, of a clutch for connecting it with a source of power, a planetary saw shaft carried by said shaft, a second clutch for connecting the saw shaft with said source of power, and separate means for automatically throwing out each clutch when the knife shaft has completed a revolution.

14. In a stereotype plate finishing machine, the combination with a longitudinal shaving knife shaft, of a saw shaft rotatably carried thereby and movable bodily out and in, an outside and inside gear rotatable on the knife shaft, a clutch for connecting said gear with a source of power, a pinion meshing with said inside gear to be driven thereby and having connections for rotating the saw shaft, a starting handle having means for throwing in said clutch, and means for automatically locking the handle in operative position.

15. In a stereotype plate finishing machine, the combination with a longitudinal shaving knife shaft, of a saw shaft rotatably carried thereby and movable bodily out and in, a gear rotatable on the knife shaft, a clutch for connecting said gear with a source of power, a pinion meshing with said gear to be driven thereby and having connections for rotating the saw shaft, a starting handle having means for throwing in said clutch, means for automatically locking the handle in operative position, means carried by the knife shaft for automatically unlocking the handle when the knife shaft has completed a revolution, and means for then restoring the handle to inoperative position.

16. In a stereotype plate finishing machine, the combination with a longitudinal shaving knife shaft, of a saw shaft rotatably carried thereby and movable bodily out and in, a clutch for connecting the saw shaft with a source of power, a lever for operating the clutch, a movable starting handle having a cam surface, a spring for holding said lever in contact with said handle in the path of said cam surface, whereby the handle controls the position of the clutch, and automatic means for locking the starting handle in a position to hold the clutch closed.

17. In a stereotype plate finishing machine, the combination with a shaving knife shaft and a cutting off saw shaft mounted to rotate with the shaving shaft and also to rotate on its own axis, of a gear concentrically mounted on the shaving shaft, means

for driving said gear independently of the shaving shaft, a clutch for connecting said gear with a source of power, means carried by said shaving shaft for rotating the saw 5 shaft on its own axis independent of said gear, a lever for operating the clutch, a starting handle having a cam surface adapted to engage said lever and hold it in position to close the clutch, a gear for driving 10 the shaving shaft, and means operated by the last named gear for releasing said handle and allowing it to be drawn back to a position to open the clutch.

18. In a stereotype plate finishing machine, the combination with a shaving knife shaft and a cutting off saw shaft mounted to rotate with the shaving shaft and also to rotate on its own axis, of means for driving 15 said shaving shaft, a clutch for connecting said shaving shaft with a source of power, means for rotating the saw shaft on its own axis, a lever for operating the clutch, a starting handle adapted to hold said lever in 20 position to close the clutch, and means for 25 releasing said handle and allowing it to be drawn back to a position to open the clutch.

19. In a stereotype plate finishing machine, the combination with a shaving knife shaft and a saw shaft mounted to rotate therewith 30 and to rotate on its own axis, a clutch adapted to connect the saw shaft with a source of power to rotate it independently of the shaving shaft, a lever for operating the clutch, a starting handle having a cam 35 surface for operating said lever and provided with a tooth and a slot, means operated by the shaving shaft for engaging said tooth and locking the handle in a position to hold the clutch closed and for releasing it from 40 that position, a spring for drawing the handle back to inoperative position when released, and means controlled by said slot for moving said saw shaft bodily into and out of operative position.

45 20. In a stereotype plate finishing machine, the combination with a shaving knife shaft and a saw shaft movably mounted thereon and rotatable on its own axis, a starting handle having means for setting the saw shaft into 50 rotation and provided with a slot, an oscillatable cam having a projection adapted to enter said slot and to be oscillated in one direction by contact with the end of the slot when the starting handle is moved to extreme position, means for moving the cam 55 back, and means carried by the shaving

knife shaft for engaging said cam and controlling the motion of the saw shaft into and out of operative position.

21. In a stereotype plate finishing machine, the combination with a shaving knife shaft and a saw shaft parallel therewith and mounted thereon movably, of a stationary cam substantially concentric with said shaving knife shaft having a notch, a frame 60 connected with the saw shaft adapted to be oscillated to move the saw shaft into and out of operative position and provided with a tooth adapted to engage in said notch to lock the saw shaft in inoperative position, a 65 roll on said frame, an oscillatable cam substantially concentric with the first cam having a notch for receiving said roll and moving it by the oscillation of the cam into and out of position to hold the saw shaft in 70 position to saw through a plate, and means for oscillating said cam.

22. In a stereotype plate finishing machine, the combination with a shaving knife shaft and saw shaft parallel therewith and 80 mounted thereon movably, of a stationary cam substantially concentric with said shaving knife shaft having a notch, a frame connected with the saw shaft adapted to be oscillated to move the saw shaft into and 85 out of operative position and provided with a tooth adapted to engage in said notch to lock the saw shaft in inoperative position, a starting handle, and means controlled by the starting handle for moving said tooth out of 90 the notch.

23. In a machine for finishing tubular stereotype printing plates, the combination with a stationary cylindrical support for a plate, of a guide longitudinally located 95 therein having means for engaging the opposite edges of the longitudinal space in the plate to guide it into proper position, and a limit stop on said guide for contact with the end of the plate.

100 24. In a machine for finishing tubular stereotype printing plates, the combination with a stationary cylindrical support for a plate, of a guide longitudinally located therein having means for engaging the opposite edges of the longitudinal space in the plate and guiding it into proper position and also guiding it in removing it therefrom.

In testimony whereof I have hereunto affixed my signature.

HENRY A. WISE WOOD.
